UNITED STATES PATENT OFFICE.

WILLIAM T. BALDWIN, OF EAST RADFORD, VIRGINIA.

DESIGN FOR A COVER FOR CLOSET-SEATS.

SPECIFICATION forming part of Design No. 32,290, dated February 27, 1900.

Application filed December 19, 1899. Serial No. 740,947. Term of patent 14 years.

To all whom it may concern:

Be it known that I, WILLIAM T. BALDWIN, a citizen of the United States, residing at East Radford, in the county of Montgomery and State of Virginia, have invented and produced a new and original Design for a Cover for Closet-Seats, of which the following is a specification.

This invention relates to a new and useful design for a cover for closet-seats; and the essential feature thereof resides in an elongated body having an opening therein of elongated form, provided with concave side walls having an angular intersection at the rear and terminating at the front at diametrically opposite points on opposite sides of an entrant flap, having a greater part of its edge in the arc of a circle, and opposite side portions parallel with the adjacent parts of the side walls of the said opening, and thereby produces a heart-shaped appearance in the center of the cover.

The figure of the drawing is a plan view of the cover embodying the features of the design.

The numeral 1 designates an elongated body constituting the cover, having an open-

ing 2 therein with opposite concave side walls 6 angularly intersecting at the rear, as at 7. The walls 6 terminate at the front at diametrically-opposite points, as at 4, and between the same is a narrow flap 3, which enters the opening 2 a short distance and has the major portion of its edge 8 convex. The opposite front side portions of the edge of the tongue are formed in abrupt angular planes to the edge 8 and parallel with adjacent portions of the side walls 6 of the opening 2. The front end of the body 1 is of compound convex contour, as at 5, and the curves unite in the center in an entrant angular recess 10. The curves 5 at their outer extremities intersect the parallel side edges 11 of the body.

Having thus described the invention, what is claimed as new is—

The design for a cover for a closet-seat, herein shown and described.

In testimony that I claim the foregoing as my own I have hereto affixed my signature in the presence of two witnesses.

WILLIAM T. BALDWIN.
